UNITED STATES PATENT OFFICE.

HENRY G. REINIGER, OF RATHDRUM, IDAHO.

SCREW.

984,969.

Specification of Letters Patent. Patented Feb. 21, 1911.

Application filed September 16, 1910. Serial No. 582,357.

To all whom it may concern:

Be it known that I, HENRY G. REINIGER, a citizen of the United States, residing at Rathdrum, in the county of Kootenai and State of Idaho, have invented certain new and useful Improvements in Screws, of which the following is a specification.

The invention relates to improvements in screws such as are employed in fastening together stove-pipe sections.

It has for its object the provision of a device that can be easily applied and removed and which, when in place, will be secure against accidental displacement.

15 It consists of a screw of the novel construction hereinafter described, pointed out in the appended claims, and illustrated in the accompanying drawings.

In the accompanying drawings, in which 20 similar reference characters designate corresponding parts, Figure 1 is a side elevation of a screw embodying the invention. Fig. 2 shows the screw applied to a joint.

The shank *a* of the screw tapers toward 25 its point *b*, and is provided with a thread *c* square in cross-section. The outer extremity *d* of the thread ends a short distance from the point *b*, and the inner extremity *e* ends at the shoulder *f* of the shank 30 a short distance from the head *g* of the screw. The head *g* is of the usual formation except that it has a beveled inner face *h*. Between the head *g* and the shoulder *f* is the neck *i* of reduced diameter, the latter being less than the diameter of the threaded 35 shank.

In applying the screw the end of one pipe-section is inserted in the end of another so that their edges overlap, and by means of 40 a suitable implement coincident holes are punched through the metal of the overlapping edges. The coincident holes should be of less diameter than the threaded shank, but sufficiently large to admit the point *b*.

45 After the holes have been formed the point *b* is inserted and the shank forced in until the outer extremity *d* of the thread engages the

edges of the metal of the overlapping pipe-sections. Then by means of a screw-driver the screw is turned through the coincident 50 holes until the edges of the metal clear the shoulder *f* and spring around the reduced neck *i*. As the neck *i* has less diameter than the threaded shank and as the metal around the holes has contracted, the screw 55 cannot be shaken loose or otherwise accidentally displaced.

To remove the screw, a flat implement such as a screw-driver is inserted between the beveled face *h* of the head and the pipe-section to slightly force outwardly the screw so that the extremity *e* of the thread will engage the edge of the metal. At the same time by means of a screw-driver the screw is turned until the thread engages the metal 65 of the pipe and the screw is turned out of the coincident openings. As soon as the extremity *e* engages the edge of the metal of the pipe the blade can be removed from beneath the head of the screw.

Having thus described my invention, what I claim and desire to secure by Letters-Patent is,

1. A screw comprising a head, a pointed shank, a thread extending along the shank 75 with its extremities ending short distances from the head and pointed end respectively, and a neck between the inner extremity of the thread and the head, said neck being of less diameter than the threaded shank. 80

2. A screw comprising a head with a beveled inner face, a pointed shank having a shoulder near its inner end a short distance from the head, a neck of reduced diameter between the shoulder and head, and a thread 85 on the shank extending from the shoulder to within a short distance of the point of the shank.

In testimony whereof I hereunto affix my signature in the presence of two witnesses. 90

HENRY G. REINIGER.
